UNITED STATES PATENT OFFICE.

CLYDE LEE NICHOLS, OF LOUISVILLE, KENTUCKY.

AUTOMATIC STEAM SHUT-OFF.

Application filed November 30, 1927. Serial No. 236,814.

This invention has reference to locomotives or steam engines, and aims to provide novel means for automatically cutting off the steam in the main steam line that supplies the 5 coaches of the train coupled with the locomotive with steam.

An important object of the invention is to provide means whereby a control valve will be actuated should the engine or locomotive 10 leave the track or turn over, or should a rear end collision occur.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within 15 the scope of what is claimed, without departing from the spirit of the invention.

Referring to the drawings:

Figure 1 is a vertical sectional view through an engine cab illustrating a device constructed in accordance with the invention as 20 installed therein.

Figure 2 is a transverse sectional view through the cab.

Figure 3 is a sectional view through the 25 housing in which the valve control rod moves.

Referring to the drawings in detail, the reference character 5 designates the boiler of the locomotive, the same being supplied with the usual steam dome 6, into which the main 30 or supply pipe 7 extends.

The pipe 7 is connected with the pipe 8 by means of the elbow 9, the pipe 8 being connected with the vertical pipe 10 by means of the elbow 11.

Strapped to the pipe 8, is a valve cylinder 12 in which the piston 13 operates, the piston 13 being connected with the valve arm 14, through the medium of the valve link 15, the lever 14 being connected with the valve 16 40 in such a way that movement of the piston 13 will result in a relative movement of the arm and valve to open or close the pipe line 8.

The reference character 17 designates a feed pipe that establishes communication between the pipe 7 and cylinder 12, there being 45 provided a valve 18 for controlling the passage of steam through the pipe 17. An arm 19 connects with the valve, which arm in turn connects with the movable bar 20, which also 50 has connection with arms 21, 22 and 23, all

of which connect with valves for purposes to be hereinafter more fully described.

The pipe 24 connects with the opposite end of the cylinder 12 and also connects with the pipe 8 to supply steam to the opposite end 60 of the cylinder 12. At one end of the bar 20 is a bell crank lever 25 to which the vertical rod 26 is connected, there being provided a transverse bar 27 carried at the upper end 65 of the rod 26.

This bar 27 operates within the housing 28 that is provided with an upstanding portion 29 formed with segments 30, the ends of the segments being spaced apart so that when the housing is rotated, to bring the bar 27 70 over the spaces between the segments, the bar will move downwardly to operate the valves connected with the valve arms 19, 21, 22 and 23.

This action of the valve arm is accomplished by the movement of the bar 20 which supports a coiled spring 31 at one end thereof, the coiled spring being normally under tension to move the bar 20 when the housing 28 is moved to release the bar 27. 75

The housing 28 is mounted at the lower end of the rod 32 which in turn is mounted in the bracket 33, and as shown, this rod 32 carries a disk 34. Actuating rods 35 extend laterally from the disk 34 and have 80 pivotal connection with the disk in such a way that inward movement of the rods 35 will produce a rotary movement of the housing 28 to release the bar 27.

Extending through the forward portion of the cab is a rod 36 which also has pivotal connection with the disk 34 so that should this rod 36 be pushed rearwardly, the disk 34 will be operated to rotate the rod 32 and consequently move the housing 28 in a manner 85 as described.

Extending rearwardly from the cab is a rod 37 that also connects with disk 34 to move the disk when inward pressure is brought to bear thereon. Mounted on the outer end of each 90 rod is a curved contact member 38 that presents a substantially broad surface for contact with an object to actuate the rods, should the locomotive leave the rails and turn over.

Connected with the under side of the disk 34 is an actuating rod 39 that connects with the bell crank lever 40 that in turn connects with the rod 41 that is mounted on the feed pipe 42, with the result that when the rod 41 is pushed towards the pipe 42, the bell crank 105 110

lever 40 will be operated to move the disk 34 in a manner as described, which in turn operates the valve.

The pipe 10 extends into the steam chest 43 through which the steam passes to the various steam pipes of a locomotive or cars connected with the locomotive.

From the foregoing it will be obvious that should a train or locomotive equipped with a device constructed in accordance with the invention turn over on its side, one of the bars 35 will be pushed inwardly operating the housing 28 to release the bar 27, permitting the valve 31 to actuate the rod 20, moving the valves to allow steam to pass into the cylinder 12.

It follows that as the steam enters the cylinder 12 the piston 13 is moved rearwardly, operating the valve 16 through the link 15, and arm 14, and cutting off the steam to the supply pipe. Should a rear end collision occur, it is obvious that the rod 41 will be forced inwardly operating the housing and valves in a similar manner to cut off the supply of steam.

I claim:

1. In combination with the main steam

supply pipe of a locomotive, a valve for controlling the passage of steam through the steam pipe, rods extending from the locomotive, a disk to which the rods are connected, said rods adapted to rotate the disk when the rods are pressed inwardly, and means controlled by the movement of the disk for operating the valve to cut off the passage of steam through the main steam supply pipe.

2. In combination with the main steam supply pipe of a locomotive, a valve for controlling the passage of steam through the main steam supply pipe, a rod supported within the cab of the locomotive, a disk carried by the rod, a housing at the lower end of the rod and having openings, a rod carrying a bar at its upper end positioned within the housing, said housing adapted to move to bring the openings thereof directly under the bar, means for moving the last mentioned rod and simultaneously operating a valve to actuate the first mentioned valve, and rods connected with the disk for rotating the disk.

In testimony that I claim the foregoing as my own, I have hereto affixed my signature.

CLYDE LEE NICHOLS.
